UNITED STATES PATENT OFFICE.

EUGENE VON VARGYAS, OF WASHINGTON, DISTRICT OF COLUMBIA.

DESIGN FOR A HEADLIGHT ATTACHMENT.

● 54,487.

Specification for Design.

Patented Feb. 10, 1920.

Application filed September 9, 1919. Serial No. 322,763. Term of patent 3½ years.

To all whom it may concern:

Be it known that I, EUGENE VON VARGYAS, a citizen of the United States of America, residing at Washington, in the District of Columbia, have invented a new, original, and ornamental Design for a Headlight Attachment, of which the following is a specification, reference being had to the accompanying drawing, forming a part thereof.

The figure is a view in perspective of a headlight attachment, showing my new design.

I claim:—

The ornamental design for a headlight attachment, as shown.

EUGENE VON VARGYAS.
